OIL BURNER

Monroe Brittain, Chickasha, Okla.

Application May 21, 1936, Serial No. 81,086

1 Claim. (Cl. 158—74)

The invention relates to a burner construction and more especially to an oil burner.

The primary object of the invention is to provide a burner of this character, wherein a trough is arranged therein for receiving oil preheated so that this oil will be conveyed to a mixing chamber at the tip of the burner nozzle, the oil being advanced in the trough through heated air and a vacuum as created in the nozzle thus a proper mixture of oil, hot air and steam is assured for a burning fuel without creating black smoke and assuring perfect combustion, a saving in oil and resultant uniform heat in a fire box of a locomotive or other fired apparatus.

Another object of the invention is to provide a burner of this character, wherein the same involves means for effectively preheating the oil and the air and to deliver the requisite amount of preheated oil to the steam prior to the latter reaching the burner nozzle tip or the steam discharge tip of such burner, the supply of air to the burner being taken from the atomizer and heated before mixture with the oil and steam at the flame tip of the burner nozzle.

A further object of the invention is to provide a burner of this character, wherein the construction thereof enables the oil to be broken up with hot air and steam prior to consumption.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a top plan view of a burner constructed in accordance with the invention.

Figure 2 is a vertical longitudinal sectional view through the burner.

Figure 3 is a rear elevation.

Figure 4 is a sectional view on the line 4—4 of Figure 2 looking in the direction of the arrows.

Figure 5 is a sectional view on the line 5—5 of Figure 2 looking in the direction of the arrows.

Similar reference characters indicate corresponding parts throughout the several views in the drawings.

Referring to the drawings in detail, A designates generally the burner constructed in accordance with the invention and includes a tube-like burner nozzle 10 having an outwardly tapered contracted burner end 11 formed with a flared side walled mouth 12 constituting a mixing chamber 13, the other end of this nozzle being fitted

with a plug 14 which is adjustable and carries a steam jet 15 which is provided at the end next to the mouth 12 with an outwardly tapered atomizing tip 16. This atomizer is adapted for connection with the steam system of a locomotive and through the instrumentality of the plug 14 such jet 15 is readily adjustable within the nozzle 10 to change the position of its tip 16 with respect to the mouth 12 and the mixing chamber 13 provided thereby.

Above the mixing chamber 13 is an oil bowl 17 having a central vertical discharge column 18 while about this column is the chamber 19 for oil content of such bowl. The bowl 17 has a removable top or cap 20 formed with a center vent 21, the cap or top being detachably fitted in the upper open end of the bowl 17 in any desirable manner.

The bowl 17 is joined with a tubular conduit 22 which opens through the outer side wall of said bowl 17 and through the medium of a substantially T-shaped union 23 and a nipple 24, respectively, is joined with the nozzle 10, the nipple 24 being vertical and closed at its upper end 25. This T-shaped union 23 has suitable connection with an oil supply (not shown) so that such supply will be delivered through the conduit 22 into the bowl 17 in the operation of the burner.

The column 18 within the bowl 17 terminates short of the top or cap 20 and opens at its top end into the chamber 19 and at its bottom end in the direction of the mouth 12 while the upper open end of said column 18 has formed therein diametrically opposite substantially V-shaped notches 26 so that oil may flow through these notches 26 into the column 18 and drop into the mouth 12 where it will be ignited in the operation.

Within the conduit 22 is a relatively small oil delivery pipe 27 carrying at opposite ends the elbows 28 and 29, respectively, the latter being connected by a nipple 30 mounted in the closed end 25 of the nipple 24 for communication with the nozzle 10.

On opposite sides of the conduit 22 and in spaced parallel relation thereto are air inlet pipes 31, these being fitted in vertical offsets 32 formed on the bowl 17 exteriorly thereof having the vertical passages 33 with which pipes 31 communicate while on the ends of pipes 31 remote from the offsets 32 are perforated air inlet heads 34 for the admission of air from the atmosphere into the pipes 31. Leading from the offsets 32 beneath the said pipes 31 are air delivery pipes 35, these being parallel with and spaced from the said pipes 31 and from a T-shaped union 36

having communication by a nipple 37 with the nozzle 10 close to the plug 14 adjustably fitting the same.

The union 23 is formed with brackets 38, these 5 supporting the pipes 31 at the rear portion of the burner.

Superimposed upon the top portion of the jet 15 is an oil trough 39 which extends from a point forward of the nipple 37 to a point 40 slightly 10 protruding beyond the atomizer tip 16. This trough 39 is positioned for receiving oil from the pipe 27 taken from the chamber 19 in the bowl 17 and delivers such oil to the mouth 12 forwardly of the atomizer tip 16, the oil being drawn 15 forwardly in the nozzle 10 through the trough 39 by vacuum created under the action of the atomizer tip 16 and this oil mixes with the steam from the atomizer 15 and hot air within the nozzle 10 to assure a perfect combustion of the fuel 20 when the burner is operated and a minimum consumption of oil at the mouth 12.

Threaded in the nozzle 10 forwardly thereof are set screws 41 which center the atomizer 15 within the said nozzle 10 and also engage with 25 the trough 39 as will appear from Figure 2 of the drawings.

The lower ends of the passages 33 in offsets 30 32 are fitted with closure plugs 42 which when removed will permit the convenient cleaning of the passages 33.

The nozzle 10 and the conduit 22 are readily cleaned when the occasion requires as the plug 14 can be removed from the nozzle 10 and the bowl 17 removed from the conduit 22 or the said 35 conduit may be detached from the union 23 should this be required.

A burner of this character will afford maximum heat with a minimum consumption of fuel 40 and is so constructed that the nozzle will be fed with the proper mixture of steam, air and oil at all times and especially when the locomotive is at rest and not requiring a large quantity of steam in its boiler. In the working of the burner

black smoke will be eliminated or reduced to a minimum within the fire chamber of the boiler.

The oil flowing through the conduit 22 and into the bowl 17 will be preheated at the flame mouth 12 and likewise the air admitted to pipes 31 and delivered through pipes 35 to the nozzle 10 taken from the atmosphere will be heated so that hot air will be present within the nozzle and the steam jet 15 will also function to heat this air prior to the mixing of the hot air with the pre-heated oil so that a perfect working of the burner is assured when in service. The oil within the trough 39 has a positive flow in the direction of the mixing chamber 13 constituted by the mouth 12 of said burner. 10 15

What is claimed is:

An oil burner comprising a tube-like burner nozzle having a tip formed with a side walled flared mouth constituting a mixing chamber, a plug adjustably fitted in said nozzle at the end 20 remote from the tip, a steam jet pipe passed through the plug into the said nozzle and having a tip within the tip of said nozzle, means engaged in said nozzle for adjusting the jet pipe, an oil trough superimposed upon said jet pipe 25 and having an inclined end overhanging the tip of said jet pipe, an oil bowl above the mixing chamber and having a central vertical discharge column and a vented cap above said column, said oil bowl being provided with air heating passages 30 in its side wall, a tubular conduit leading to the bowl and connected with the said burner nozzle, an oil delivery pipe extended through the conduit into the bowl and into the nozzle through the connection of the conduit therewith and terminating above the trough within said nozzle, air inlet pipes arranged at opposite sides of the conduit and opening from the atmosphere into the said air heating passages, and air delivery pipes parallel with the air inlet pipes and leading from the said bowl into the nozzle at a point rearwardly from the trough therein for the delivery of preheated air into the said nozzle. 35 40
